Attorney

pler head to the car body and the cooperation between the head and attaching means and the effect upon the operation of the car to which my advance in the art relates principally and not in the type of head per se. The two heads could be of the same design if so constructed as to intercouple, as shown for instance in U. S. Letters Patent 2,140,705 issued to me December 20, 1938.

My description therefore, covers principally the means of attaching the coupler head to the car body and their correlation and operation and, for that reason I have not shown in detail the companion head as that is clearly shown and described in my Patent 2,235,618.

In Fig. 1, the male coupler M comprises in general a head 1, a draw bar 2, and a resilient anchorage 3 and these parts are shown assembled and mounted on a car body A.

In Fig. 1, the female coupler F comprises a head 4 which has integrally combined with it a draw bar 5, and the resilient anchorage 3 attached to a car body B.

The female head 4 is adapted to receive the male head 1 and the two are locked in coupled position by the latch 7 which engages the bearing face 8 in the transverse slot 9. The handle 10 secured to the latch 7 operates the same to the unlocking position.

The resilient anchorage 3 is the same for both types of heads and comprises a box-like member 11 formed with a back member 12 and side members 13 and held to the car body by bolts 14 which also secure in place the parts within the member 11.

Mounted within the member 11 is a pad 15 preferably of resilient or elastic rubber capable of returning to its original shape after deformation. The pad 15 is provided, on its front face, with a plurality of spaced ribs 16 at or adjacent the extreme side edges thereof and the ribs are connected by an extended flat portion 17 in which is embedded a metal plate 18 as by moulding and/or vulcanizing at the time of manufacture.

Mounted upon the front of the pad 15 and engaging the ribs 16 is a metal clevis member 19. Mounted within the anchorage casing is a yoke shaped member 21 having a vertical portion in front of each elastic member 20 and also having portions extending rearwardly and engaging the back members 12 and held in place by bolts 14 and nuts 22 thereon. The members 21 are designed to meet specific conditions and when mounted into place, a normal compression is placed upon the resilient members 16 and 20 and this compression is maintained by the nuts 22.

The rubber parts 15 and 20 are employed in place of metal springs and have proven superior thereto and require less space for equivalent work. I may use in place of "rubber," the various forms of so called synthetic rubber and elastic plastics, which my term "rubber" includes and which are non-metallic.

The coupler head is mounted on the clevis member 19 by means of the pin 23 which permits pivoted movement of the head in a lateral direction relative to the anchorage and car. The support member 19 and head 5 move longitudinally together under pull or buff action.

In Figs. 2 and 3 the parts are shown in normal relation. Under a draft or pull the coupler head and member 19 will move forward and thereby compress the rubber springs 20 and relieve some of the normal pressure on the rubber ribs 16.

In Fig. 4 the parts are shown under approximately a maximum buffing action applied directly along the longitudinal axis with the end 5' of the coupler engaging the plate 18 at which a tendency to align the couplers and cars begins to act, the ribs 16 being fully compressed. With less buffing action, the ribs 16 would have been only partly compressed and the coupler end would not contact the buffing plate 18.

When the pressure due to the buff is released the spring action of the rubber ribs 16 tends to force the parts to their normal position as in Fig. 2.

It will be noted that in my prior invention disclosed in the aforesaid Patent 2,235,618, that all pressure due to buff is distributed over the entire area of the rubber spring or pad while in my present invention the normal buff is taken up by ribs 16 at points laterally spaced from the longitudinal center of the device until the buff exceeds the resistance thereto by the resiliency of the ribs 16.

Mounted within the coupler head near its pivoted end is a slidable centering device 24 (Fig. 2) having a forked end with tines 25. These tines rest against the member 19 in both grooves 26 when the head is in a normal position (Fig. 2).

The tines are pressed against the member 19 by means of the spring 27 held at one end by the fixed pins 28. The pressure of the spring 27 is sufficient to maintain the coupler head in longitudinal alignment with the car axis when uncoupled.

The action of this centering device is the same as that disclosed in the aforesaid Patent 2,235,618 namely, when the coupler head is moved laterally to one side (Fig. 12) the spring 27 is compressed thus increasing its normal pressure and increasing the tendency to move the head to its central position.

In further explanation of the purpose and operation of my invention, I show schematically in Fig. 5 a train of cars connected by the conventional type of pivoted couplers and attachments in which the cars are under draft conditions or in a normal state that is neither draft nor buff. The couplers are longitudinally aligned with the longitudinal axis of the train.

In Fig. 6 is shown schematically the effect of the same equipped cars under buff conditions in which the cars are buckled due to the clearance between rail head and wheel flanges and the couplers freely pivoted relative to the cars. The tendency is to push the cars from the rails.

My improved coupler eliminates the tendency of cars to buckle under buff forces and on the contrary has the effect of aligning the cars longitudinally in a straight line parallel to the rails when subjected to severe or abnormal buffing.

In Fig. 7 is shown schematically a train of cars equipped with my improved coupler and anchorage under buff conditions and it will be noted the cars and the couplers pivoted thereto remain aligned longitudinally.

The support member 19 rests upon the raised ribs 16 which are under sufficient compression to maintain the member 19 in its forward position when uncoupled (Fig. 2) or when coupled but under neither buff nor draft forces. The adjacent ribs 16 are spaced and this together with their construction permits them to be fully compressed under sufficient or abnormal buff forces.

In operation, if a haulage train is made up of cars of a size and construction commonly used in mining and industrial work and equipped with

conventional type couplers (Fig. 6), experience has shown that a compression or buff force of less than 5,000 pounds is not sufficient to cause a derailment of the cars but when a buffing force of more than 5,000 pounds is encountered the tendency for the cars to climb the rails is present and this tendency increases as the buffing force increases.

If the cars of such a train are equipped with my improved couplers constructed to overcome the above detrimental conditions, that is, to operate with unrestricted lateral movement under normal buffing conditions and when abnormal conditions are met, the couplers will tend to prevent derailment by operating to force the cars into alignment and to maintain such alignment.

The coupler equipment would be constructed, let us say, to have about $\frac{1}{8}$ inch longitudinal movement of the coupler body relative to the anchorage at 5,000 pounds buffing force, while a movement of $\frac{3}{4}$ inch would just seat the broad end face 5' of the body against the buffing plate 18.

As soon as the said end face 5' engages the buffing plate 18, at a force somewhat less than 5,000 pounds (Figs. 4 and 7), the compression force will begin to exert an effort to bring the cars and couplers into alignment. When a buffing force of 5,000 pounds is reached, the plate 18 will be under considerable compression and will exert a considerable moment of force to bring into and maintain alignment of the cars and couplers, and the greater the buffing force the greater the moment of force exerted.

The buffing force acting between the end of the body 5 and the buffing plate 18 is exerted at the lateral edges of the body 5 and hence produces a moment at one edge or the other, depending upon which direction tendency for non-alignment is exerted, and this moment is substantially the product of the buffing or compression force times one-half the width of the coupler end face at each coupled end of the car.

After being subjected to a compressive or buffing force of about 5,000 pounds the coupler and car axes will align with practically the complete surface of buffing plate 18 in contact with the rear end of the coupler body and with the rear face of clevis member 19 and any additional compressive force will be absorbed by the entire rubber member 15 which may be of sufficient size and consistency to absorb a compressive force of 50,000 pounds or more at the end of an additional compressive movement of $\frac{1}{2}$ inch.

The members 20 will yield against a pulling or draft force.

In my previous description it is evident the coupler head may pivot on the pin 23 under normal buffing and pulling conditions and even when the coupler is under extreme compression it may be moved laterally under influence of a laterally applied force such as would be the case if the cars were pushed around rather sharp curves. In this case one lateral edge of the rear face of the coupler body will rock over sufficiently to engage the plate 18 thus bringing pressure on one edge of the coupler body end face and of the resilient pad 15 and releasing pressure on the other edge thereof (Fig. 12).

In Fig. 8 is shown diagrammatically a form of difficulty sometimes experienced when coupling cars on short curves with automatically centering coupler heads. The couplers are held in a central position and the condition of the curve projects the face of the coupler in one car far

enough out of the center line of the track so that it is missed by the coupler on the companion car which is being moved forward to effect a coupling.

5 In my improved coupler I propose to overcome this difficulty by providing means to hold the coupler head in a lateral position. I provide a notch 29 in the face of the plate 18 so that when the coupler head is manually swung over to either 10 extreme position a corner at the rear end of the coupler head will enter the notch and hold the head in its lateral position against the pressure of the centering device until released automatically by sufficient external force as by the coupling of the cars or when released manually. In Fig. 11 the head is swung around almost sufficiently for the corner of the head to enter the notch 29. In Fig. 9 the couplers are shown as equipped with notch 29 and the coupler D is held in a position to couple with the companion coupler upon bringing the cars together.

A further and important advantage of my improved invention is diagrammatically shown in Fig. 10 which shows three cars U, V, and W equipped with my improved coupling device and operated on a 20 foot radius curve.

The cars are assumed to be pushed around the curve in the direction of the arrow and the pushing force is assumed to be large enough to compress the resilient ribs 16 of the resilient pads 15 so that the flat end faces of the coupler heads come in contact with the plates 18 of the pads 15.

The cars U and V are each on the curve and car W is still on tangent track approaching the curve with the coupler pivot 22 on the point of tangency. Thus the position of the couplers at X between the cars V and W shows the position assumed by the couplers when one car is on the curve and the other car with the coupler pivot on the point of tangency.

In this position the coupler X on the car V takes the maximum swing attainable by normal operation over a 20 foot radius curve with a car of such proportions as shown (10' x 6' body) and the coupler on car W is at the starting stage of its cycle of lateral swing with the center line only out a few degrees from the center line of the car.

Assuming that a pushing force P is exerted 50 from car W against car V, it will be noted that the direction of this would be along the line 50, through the pivoted centers of the couplers if conventional couplers with unrestricted swing are used, but the force is along the line 51 connecting diagonal corners of the end faces of the coupler heads when my improved coupler equipments are used. Fig. 11 exemplifies my improved equipment at X.

The force P in addition to moving the cars W and V along the track also produces a twisting moment acting on each car tending to push the respective car off the track. In the case of car W this moment is equal to $P \times A$ when the conventional coupler is used, and it is zero when my improved coupler equipment is used because the line 51 passes through the vertical center line of the car showing that the tendency to push car W off the track is infinitely reduced by the use 60 of my improved equipment.

In the case of car V, the moment of force is equal to $P \times B$ when conventional couplers are used, and to $P \times C$ when my improved coupler is used, and as C is considerably less than B, the 65 equations show that the tendency to push the

car V off the track is considerably reduced by the use of my improved coupler.

At Z in Fig. 10 is shown the position assumed by the couplers when two adjacent coupler cars U and V are both on a 20 foot radius curve. The lateral swing of the couplers in relation to the car center lines are then the same in both cars and, assuming a pushing force P' exerted from car V to car U there is a moment of force produced tending to push both cars U and V off the track equal to $P' \times E$ when conventional couplers are used and equal to $P' \times D$ when my improved couplers are used.

As D is less than E the equations show that the tendency to push the cars off the track in this position is also less when my improved couplers are used than when conventional couplers are used.

In Fig. 11 is shown the approximate relation of the parts of my improved coupler at the maximum swing, as at X in Fig. 10, with particular emphasis on the compression of the rubber buffering pad 15 under influence of the compressive force P.

In Fig. 12 is shown the approximate position of the coupler parts at a lesser degree of swing, such as at Z, showing how the rubber block 15 is compressed at one end and released of compression at the other end under the influence of the unequal distribution of the force P.

The wider I make the rear end face of my improved coupler, the greater is the effect described above but with an end face of 4" to 6" in width I am able to secure very marked results in improved operation.

In order to help support the coupler head in a horizontal position, I place two spaced coil springs to exert pressing upon the clevis member 19 adjacent its lower edge, thus tending to raise the coupler and assist in holding it in a horizontal position.

In the appended claims I have used certain expressions which are defined as follows—

Normal buffering force is any such force less than that which will derail the car. In the example given above, it is any buffering force less than 5,000 pounds.

Normal longitudinal moment refers to the longitudinal movement in either direction and if in a buffering direction it is limited to normal buffering force.

The support member 19 is held in a normal position when its plane is normal to the longitudinal axis of the coupler body 5.

The longitudinal axis of the anchorage is its axis which aligns with the longitudinal axis of the car to which it is attached. Under practically all construction the longitudinal axes of the coupler proper, of the anchorage and of the car are in alignment under draft conditions except when operating on curves.

The coupler proper is in its central position when its axis is aligned with that of the car or anchorage.

The coupler proper is in its central position when it is substantially free of draft and buffering forces as when uncoupled from a companion coupler.

The size of the various parts of my invention may be changed to meet various conditions especially with respect to the size and construction of the car and the buffering forces to which it will be subjected.

Having described my invention, that which I claim is set forth in the appended claims.

I claim:

1. A coupler anchorage comprising in combination, a body member for attachment to a car, a support member with means thereon to secure a coupler body thereto, resilient cushioning means of non-metallic material interposed between the support member and the body member to permit longitudinal movement of the coupler body under either draft or buff forces, and a buffering plate associated with the cushioning means and so related thereto as to be engaged by the rear portion of the coupler body to receive a portion of the buffering force due to the rearward movement of the coupler body after the said buffering force has been initially applied to the support member.

2. A coupler anchorage comprising in combination, a body member for attachment to a car, a support member with means to attach a coupler thereto, resilient means interposed between the support member and the body member and arranged to engage with and normally hold the support member normal to the longitudinal axis of the anchorage, the said resilient means being constructed with channeled formations and so arranged relative to the support member and to the body member that the support member may be moved relative to the body member and assume obliquely disposed positions relative to the said axis under buff forces, a metal buffering plate associated with the resilient means and in axial alignment with the longitudinal axis of the anchorage, and means on the plate to be engaged by the rear end of an associated coupler to releasably hold the coupler with its longitudinal axis obliquely disposed to the longitudinal axis of the anchorage.

3. A coupler anchorage comprising in combination, a body member for attachment to a car, a support member with means thereon to secure a coupler thereto, resilient cushioning means of non-metallic material interposed between the support member and the body member to control the longitudinal movements of the coupler relative to the anchorage under either draft or buff forces, the means controlling the buffering forces extending laterally in both directions from the longitudinal axis of the anchorage and comprising raised yieldable portions at the lateral ends and which engage with the support member and exert constant forward pressure upon the support member and a central portion between said raised end portions, the central portion arranged to remain out of operative relation with the support member during normal buffering operations.

4. A coupler anchorage comprising in combination, a plate-like support member provided with means to attach a coupler thereto, a body member for attachment to a car, resilient means of non-metallic material interposed between one face of the support member and the body member, other resilient means of non-metallic material interposed between another face of the support member and fixed means secured to the body member, the said resilient means being under constant compression, the first said resilient means being subject to further compression from buffering forces and the said other resilient means subject to further compression from draft forces, the first said resilient means formed with a plurality of spaced and raised portions whereby the said normal buffering forces upon said support members are absorbed by the said raised portions.

5. In a car coupler anchorage provided with a body member for attachment to a car and a support member for pivotally mounting the coupler

on the anchorage and means of elastic non-metallic material positioned between the said support member and the body member, the combination with the body member of a resiliently mounted buffer member positioned rearwardly from the support member and arranged to be engaged by the coupler when pivoted laterally from its central position and said buffer member constructed and arranged so as to interlock with a position of the adjacent end of the coupler to retain it in its other than central position.

6. In a car coupler anchorage provided with a body member for attachment to a car and a support member for pivotally mounting the coupler on the anchorage and means of elastic non-metallic material positioned between the said support member and the body member, the combination with the body member of means positioned rearwardly from the support member and arranged to be engaged by and to yieldingly interlock with the coupler when moved laterally from its central position to hold the coupler in its other than central position.

7. In a car coupler anchorage provided with a body member for attachment to a car and a plate-like support member for pivotally securing the coupler to the anchorage, the combination with the body member of means of yieldable non-metallic material interposed between the support member and the body member and normally maintaining the support member at right angles to the longitudinal axis of the anchorage but permitting the support member to take an oblique position relative to the said axis under buffing forces applied by the coupler, and means spaced from said body member and supported by non-metallic material, said means constructed and arranged to engage and hold a portion of the adjacent end of a coupler member to retain the coupler member in an oblique position.

8. A car coupler mechanism comprising in combination, a coupler head and body, the head portion adapted to couple with the head on a companion coupler, an anchorage to mount the coupler body on a car, the said anchorage comprising a movable support member to which the body portion is pivotally attached for lateral movement, a buffer member spaced rearwardly from the support member and engageable by the rear end of the coupler body and means to resiliently secure the support member and the buffer member in position whereby both members are permitted to move longitudinally relative to the car under a buff force.

9. A car coupler comprising in combination, a coupler body including a head to couple with a companion coupler, an anchorage to mount the coupler body and head on a car, the said anchorage comprising a body portion for attachment to the car, a support member to which the coupler body is pivotally attached for lateral movement, a buffer member spaced rearwardly of the support member and engageable by the rear end of the coupler body, and means resiliently securing the support member and the buffer member in position relative to the anchorage body, whereby the coupler body and the support member are yieldable longitudinally under either a draft or a buffing force and the buffer member is yieldable longitudinally under only a buffing force.

10. Car coupling mechanism comprising in combination, a coupler head adapted to couple with a companion head, a coupler body projecting rearwardly from the head, an anchorage to mount the head and body on a car, the said anchorage

comprising a support member having means for attaching the coupler body thereto, an anchorage body adapted to be attached to the car, resilient means interposed between the support member and the anchorage body whereby the support member is held in position and the coupler head and body permitted to move longitudinally of the anchorage body under either a draft force or a buffing force, a resiliently held buffer plate positioned rearwardly from the support member in spaced relation thereto and engageable by the rear end of the coupler body only after the buff force exceeds a predetermined value.

11. Car coupling mechanism comprising in combination, a coupler including a coupler head adapted to couple with a companion coupler, an anchorage to mount the coupler body on a car, the said anchorage comprising a body portion for attachment to a car, a support member to which the coupler body is pivotally secured for lateral movement, resilient means interposed between the support member and the said body portion to cushion the normal longitudinal forces of draft and buff and a resiliently supported buffer member to be engaged by one end of the coupler body when the said normal buffing force is exceeded, to further cushion the buffing force.

12. Car coupling mechanism adapted to be mounted on a car and to couple with a companion coupler comprising in combination, a coupler head provided with a rearwardly projecting coupler body, an anchorage to mount the coupler head and body on a car, the said anchorage comprising a body portion for attachment to a car, a support member to which the coupler body is pivotally attached for lateral movement with a portion of the coupler body projecting rearwardly from the pivot pin and beyond the rear face of the support member, yielding means of elastic non-metallic material positioned between the support member and the anchorage body portion to cushion the draft and buff forces and permit longitudinal movement of said coupler head and body under said forces, a resiliently mounted buffer member positioned so as to be engaged by the said projecting portion of the coupler body when the rearward longitudinal movement of the coupler body exceeds a predetermined amount to further cushion the buffing force and to maintain the longitudinal axis of the coupler body and the anchorage in alignment during said excess rearward movement.

13. Car coupling mechanism adapted to be mounted on a car and to couple with a companion coupler comprising in combination, a coupler head provided with a rearwardly projecting coupler body having a substantially flat end surface projecting laterally to each side of the longitudinal axis of the head and body and in a plane normal to said axis for the purpose described, an anchorage to mount the coupler head and body on a car, the said anchorage comprising a body portion for attachment to the car, a support member to which the coupler body is pivotally attached to move laterally to either side of its central position with a portion of the coupler body and flat end surface projecting rearwardly from the pivotal pin and beyond the rear face of the support member, resilient means of non-metallic material positioned between the support member and the anchorage body portion to cushion the forces of draft and buff and permit longitudinal movement of the coupler head and body relative to the anchorage, a resiliently mounted buffer member having a substantially flat surface posi-

tioned so as to be engaged by the end surface of the said projecting portion of the coupler body when the rearwardly longitudinal movement of the coupler body exceeds a predetermined amount, the surface of said buffer member being normal to the longitudinal axis of the coupler head and body when in their central position whereby the longitudinal axis of the coupler body and head and of the anchorage will be brought into longitudinal alignment when the said surfaces engage, said buffer member having a formation therein engageable with the rearwardly projecting portion of the body to hold said body in an off-center position.

14. In a car coupling mechanism comprising a car coupler to couple with a companion coupler and an anchorage arranged to pivotally mount the coupler upon a car and having means of elastic material to cushion the longitudinal movements of the coupler relative to the anchorage due to draft and buff forces, the rear end surface of the coupler being substantially flat and normal to the longitudinal axis of the coupler and extending laterally on both sides of said axis, the combination with the anchorage of means to be engaged by the said end surface of the coupler after the coupler has moved rearwardly in excess of its normal buff movement to maintain the longitudinal axes of the coupler and said anchorage in alignment.

15. In a car coupling mechanism comprising a car coupler and an anchorage to pivotally mount the coupler upon a car and having means of resilient material to cushion the rearward movements of the coupler relative to the anchorage due to normal buffing forces, the combination with the anchorage of means engageable by the rear end of the coupler after the said rearward movements are exceeded to hold the longitudinal axis of the coupler and anchorage in alignment under said buff action.

16. In a transportation system comprising a train of two or more cars mounted on a track and couplers connecting adjacent cars and an anchorage secured to each car and provided with means whereby each coupler is pivotally mounted upon its car and further each anchorage provided with means to cushion the normal buff and draft forces between adjacent cars, the combination with each anchorage of cushioning means to be engaged by the adjacent rear end face of the associated coupler under abnormal buff forces to align the longitudinal axis of the car and the coupler and to maintain said alignment on a tangent track whereby derailment of the cars is resisted.

17. In a transportation system comprising a train of two or more cars mounted on a track and couplers connecting adjacent cars and an anchorage secured to each car and provided with means whereby each coupler is pivotally mounted upon its car and further each anchorage provided with means to cushion the buff and draft forces between adjacent cars and the rear end of each coupler projecting within its anchorage and having an end surface of extended width from the longitudinal axis of the coupler, the combination with each anchorage of resiliently supported means normally spaced rearwardly from the end surface of the associated coupler and having a surface of extended width normal to the longitudinal axis of the car and engageable by the end surface of the coupler under a buff force whereby due to the width of the contacting surfaces and the buffing force

a force moment is set up on either side of the longitudinal axis tending to maintain the axis of the cars and couplers in longitudinal alignment and thereby resist derailment of the cars.

18. In a haulage system comprising a train of two or more cars operating on a track and the adjacent cars connected by car couplers pivotally mounted thereon by interposed anchorages and each anchorage provided with resilient means of non-metallic material to cushion the normal draft and buffing forces relative to this anchorage, the combination with each anchorage of other resilient means to engage with means spaced therefrom on the associated coupler after the buffing force exceeds said normal force tending to derail the cars, the said other means when engaged by the last said means on the coupler under said excess buffing force providing moments of force operating to align the longitudinal central axes of the couplers and anchorages and cars and hold them in alignment thereby resisting the tendency for the cars to derail due to excess buffing forces.

19. In a haulage system comprising two or more cars operating on a track and car couplers connecting the adjacent cars and including support means to receive and pivotally secure the couplers to their respective cars and each said means provided with cushioning means of yieldable elastic material to absorb the normal draft and buffing forces, the combination with the first said means of other resilient means to be engaged by the rear end of the coupler to receive buffing forces in excess of said normal buffing forces, the rear end on each coupler co-operating with said resilient means to form moments of force spaced laterally from the longitudinal axes of the cars and the couplers whereby the couplers and cars are brought into alignment after excessive buffing and so maintained with their longitudinal axes in alignment during the period of application of said excess buffing force.

20. In a transportation system comprising a plurality of cars and a track on which the cars operate and couplers connecting the adjacent cars with the longitudinal axes of the couplers and cars in alignment on the tangent portions of the track and anchor means to pivotally secure the couplers to the cars with resilient means interposed between the couplers and the anchors and to absorb the normal buffing forces, the combination with the said anchors of auxiliary means spaced from said resilient means so arranged as to cooperate with the couplers whereby a moment of force will be developed to align the longitudinal axes of the couplers and cars when the cars are operating on a curve and the buffing force is in excess of the said normal buffing force thereby tending to derail the cars.

21. In a transportation system comprising a plurality of cars and a track on which the cars operate and couplers connecting the adjacent cars with the longitudinal axes of the couplers and cars in alignment on the tangent portions of the track and anchor means to pivotally secure the couplers to the cars with resilient means interposed between the couplers and the anchors to permit longitudinal movement of the couplers relative to the anchors and to absorb the normal buffing forces, the combination with the anchors of auxiliary means spaced from the said resilient means to co-operate with the couplers when the buffing forces exceed said normal force tending to derail the cars, the said co-operation being effected at a lateral distance from the said

longitudinal axis of the coupler whereby a moment of force is produced equal to the product of the component of the full buffering force times the perpendicular distance from the said longitudinal axis of the coupler to the point of application of the said component thereby tending to rotate the coupler on its pivotal axis to align the axes on a curve and to maintain the alignment on the tangent thereby resisting derailment of the cars.

22. A cushion for a car coupler anchorage comprising, a body of elastic non-metallic material adopted to be interposed between the coupler and anchorage, the said body having two end portions and a depressed central portion of extended area, the end portions each provided with a plurality of spaced and raised means so constructed and related to the central portion that the normal buffering forces will be absorbed by the said raised means prior to the central portion absorbing buffering forces in excess of said normal forces and a metallic plate of extended area positioned in the depressed portion to distribute the pressure due to the excess buffering forces over an extended area and to maintain the coupler in an aligned position with the longitudinal axis of the car while under excess buffering.

23. A cushion for a car coupler anchorage comprising, a body of resilient non-metallic material adopted to form a part of a car coupler anchorage and of extended area, the said body provided with raised portions so constructed and arranged as to receive and absorb the normal buffering forces of a car coupler, and the said body also provided with a depressed flat central portion to receive and absorb buffering forces in excess of said normal buffering forces and a metal plate positioned in said depressed portion and secured in place by its edges embedded in the resilient material.

24. A cushion for a car coupler anchorage comprising, a body of resilient non-metallic material adopted to form a part of a car coupler anchorage and of extended area, the said body provided with a plurality of raised rib portions at its edges so constructed and arranged as to receive and absorb the normal buffering forces of a car coupler, and the said body also provided with a depressed portion to receive and absorb buffering forces in excess only of said normal buffering forces, and metallic means of extended area associated with the central portion and secured thereto to be engaged by the rear end of the coupler to yieldingly retain said coupler with its longitudinal axis obliquely disposed to the face of said cushion and to distribute the pressure of the coupler over an extended area of said depressed portion.

25. In combination, a car, an anchorage mounted on the car, a coupler mounted on the anchorage to pivot laterally, the longitudinal axes of the

car and of the coupler being capable of longitudinal alignment, and means on the anchorage positioned rearward of the coupler end and normally spaced for said coupler end and arranged to cooperate with means on the coupler whereby the coupler and the car are maintained in longitudinal alignment when the said parts are subjected to a buffering force greater than the normal buffering force and also to bring the coupler and car into alignment from an unaligned condition.

26. In combination, a car, an anchorage mounted on the car, a coupler mounted on the anchorage to pivot laterally, the longitudinal axes of the car and of the coupler being capable of longitudinal alignment, and means on the anchorage positioned rearwardly of the coupler end and normally spaced from said coupler end and arranged to cooperate with means on the coupler whereby the coupler and the car are brought into longitudinal alignment from an unaligned position when the said parts are subjected to a buffering force in excess of the normal buffering force.

27. In a car coupler organization, a housing securable to a car, a buffering element fixed to the car and disposed within said housing, a plate secured to said buffering element, a support disposed ahead of and adjacent said buffering element, a draft element arranged ahead of said support, means holding said draft element and said support for movement relatively of each other and said buffering element, a coupler element pivoted to said support, the end adjacent the pivot spaced from said plate, said buffering element having ribbed portions engaging said support adapted to absorb the normal buffering action, and said coupler end adjacent said plate contacting said plate upon an abnormal buffering action and said plate and adjacent end of said coupler when in contact maintaining the axis of said coupler in alignment with the axis of the track on which said car is running.

28. In a car coupler organization, a housing securable to a car, a buffering element fixed to one wall of said housing, said buffering element having a plurality of raised portions along some of its edges, a plate held on said buffering element between said raised portions, a support disposed within said housing adjacent said buffering element raised portions, a draft element including a resilient element disposed ahead of said support, means to hold said draft element and said support and said buffering element in operative relation, and a coupler body pivoted to said support, the pivoted end of which is spaced from said plate, said spacing being of an amount such that said raised portions will first absorb the initial buffering action and said adjacent end of said coupler will then engage said plate to enable the entire buffering element to absorb the buffering action.
